GAS FLOW ALARM SWITCH

Application filed September 5, 1928. Serial No. 304,008.

This invention relates to gas flow alarm switch of that type adapted to give an audible signal in case the control valve of a gas burner is accidentally opened or in case the 5 gas pressure should be discontinued or unduly lowered for any reason, thereby warning the occupant of the dwelling so that any valves that may be opened may be promptly closed to avoid accidents or death resulting from the 10 escape of gas into and filling the rooms of the dwelling.

More particularly, the present invention relates to an improved form of circuit controller for an electrical gas flow alarm of the 15 above kind, and the primary object of the present invention is to provide a control of this character which is simple in construction as well as thoroughly efficient and reliable in operation.

20 A more particular object is to provide a circuit controller of the above kind embodying an expansible chamber adapted to be interposed in the gas supply line, a pair of spaced contacts movable in a given path by 25 the expansion and contraction of the chamber, and a manually adjustable contact arranged in the path of movement and between said pair of contacts so as to provide for closing of the alarm circuit when the pressure 30 in the supply line is reduced by opening the burner controlling valve and when the pressure is maintained in the line by closing said valve, the adjustment of the manually adjustable contact permitting opening of the 35 alarm circuit after each operation.

Still another object is to provide a controller of the above kind embodying simple and efficient means for insuring partial collapse of the expansible chamber when the gas 40 pressure is reduced, and to also provide for proper mounting of the pair of spaced movable contacts.

Still another object is to provide means for 45 causing the pair of spaced contacts to move in a definite path and thereby maintain effective operative relation to the manually adjustable contact.

Still another object of the invention is to 50 provide a flexible partition within the casing structure housing the electric contacts and

expansible chamber that is disposed between the contacts and expansible chamber so that any gas leaks from the chamber will be exhausted from the housing at a point remote from the eccentric contacts to eliminate all 55 fire hazards.

Other objects will appear as the nature of the invention is better understood, and the same consists in the novel form, combination and arrangement of parts hereinafter more 60 fully described, shown in the accompanying drawings and claimed.

In the drawings:—

Figure 1 is a perspective view illustrating an embodiment of the present invention interposed in the gas supply line of a cooking range, the alarm circuit being diagrammatically shown; 65

Figure 2 is an enlarged top plan view of the circuit controller shown in Figure 1, 70 with the cover plate of the casing removed;

Figure 3 is a transverse vertical section taken on line 3—3 of Figure 2;

Figure 4 is a fragmentary vertical section taken on line 4—4 of Figure 3; 75

Figure 5 is a view similar to Figure 3 showing the expansible chamber partly collapsed as when the burner controlling valve is open;

Figure 6 is a view similar to Figure 4 of the construction as shown in Figure 5, the 80 line of section being indicated at 6—6 in Figure 5;

Figure 7 is a view similar to Figure 6 showing the circuit closing relation of the contacts when the expansible chamber is allowed to collapse beyond a predetermined extent, as when the gas pressure is discontinued or abnormally reduced in the supply line; and 85

Figure 8 is an enlarged fragmentary detail 90 elevation showing a portion of the front of the controller casing and the operating knob and indicator of the adjustable contact.

Referring more in detail to the drawings, 95 5 indicates a conventional form of cooking range having a gas supply pipe 6 and provided with a plurality of valves 7 for controlling the flow of gas from the supply pipe 6 to the several burners of the stove.

The present invention is adapted to be in- 100

terposed in the supply pipe or line 6 between the source of gas supply and the valves 7 as illustrated in Figure 1 and consists of a suitable casing 8 having a top closure plate 9 and provided with side openings as at 10 to admit spaced opposed ends of adjacent sections of the supply pipe 6 as clearly shown in Figures 1 and 2, an elastic expansible chamber 11 being placed within the lower portion 10 of the casing 8 and having opposite inlet and outlet nipples 12 and 13 for connection with the adjacent ends of the respective sections of the supply pipe 6, mentioned above.

As shown clearly in several of the views, 15 the chamber 11 preferably has a somewhat flattened top wall upon which is suitably secured a cup-shaped supporting member 14 in opposite sides of the rim or flange of which are journaled the inturned ends 15 of a bail-like guide element 16 whose intermediate portion is horizontally journaled upon the inner face of the rear wall casing 8 to permit the guide element to swing vertically and thereby cause the support 14 to move in a definite path when raised or lowered by expansion or contraction of the chamber 11. The front portion of the support 14 is provided with an interior rigid weight as at 18 to yieldingly resist the expansion of the chamber 11 25 and accordingly cause positive lowering of the support 14 when the pressure within the chamber 11 is reduced or discontinued. Mounted upon the front part of the support 14, preferably by securing them on top of the weight 18 as shown, are a pair of electrically connected superposed and vertically spaced contacts 19 and 20 which are in electrical connection with a binding post 21 on the back wall of the casing 8.

40 A flexible partition 11a separates the casing 8 into upper and lower compartments and is interposed between the expansible chamber 11 and weight 18, the partition being formed of suitable leak-proof material, such as leather, rubberized fabric or the like. Openings 11b formed in the side wall of the casing 8 at the lower end thereof provide an outlet for escaping gas from the expansible chamber and to remove the escaping gas from the immediate vicinity of the contacts in the upper compartment of the casing.

55 Journalled in the front wall of the casing 8 is a horizontal shaft 22 whose inner end carries a laterally projecting contact finger 23 disposed between and in the path of the contacts 19 and 20 as shown clearly in Figures 4 and 6, the other end of the shaft 22 being equipped with a suitable knob or handle 24 whereby the shaft may be conveniently turned for vertically swinging adjustment of the contact finger 23.

In use, the contact finger 23 is normally set in the intermediate full line position of Figure 4 so that when the valves 7 are closed, the normal pressure in the supply

pipe 6 will be sufficient to expand the chamber 11 and engage the lower contact 20 with the contact finger 23, whereby the alarm circuit is closed until the shaft 22 is turned to swing the finger 23 upwardly to the dotted line 70 position of Figure 4 and thereby set in proper position for being engaged by the upper contact 19 should one of the valves 7 be accidentally opened and thereby cause such partial reduction of pressure in the chamber 11 75 to permit partial collapse of the latter as shown in Figures 5 and 6. Upon such latter occurrence, the alarm circuit will be closed, thereby giving a warning that the gas is escaping because of the accidental opening 80 of the valve 7. Obviously, when being warned of this occurrence, an occupant of the dwelling will promptly investigate and close the valve in order to stop the escape 85 of gas in sufficient time to avoid serious accident, the alarm being rendered inoperative 90 at this time by swinging the finger 23 downwardly to the dotted line position of Figure 6. As soon as the valve is turned off the chamber 11 will again expand and cause 95 the contact 20 to engage contact finger 23, the latter being then manually returned to the dotted line position of Figure 4 to again render the alarm inoperative until a burner valve control valve 7 is again opened. Should 100 the burner controlled valve be intentionally opened, the circuit closing condition of Figure 6 will again be presented, and the sounding of the alarm can be stopped by swinging the finger 23 to the dotted line position of Figure 6 or the full line position of Figure 7. With the gas in use under these conditions, 105 there is a possibility of the burner becoming extinguished due to the gas pressure being temporarily discontinued for some reason, and should this take place there is the danger of gas escaping through the open burner controlling valve when the gas flow is again continued. However, should the gas flow be 110 temporarily discontinued, the chamber 11 will further collapse to thereby bring contact 19 downwardly still further into engagement 115 with contact finger 23 as shown in Figure 7, thereby closing the alarm circuit and giving a warning so that the burner controlling valve may be closed sufficiently soon after the gas flow is discontinued, to prevent the serious escape of gas from subsequent resumption of the gas pressure. To render the alarm inoperative at this time, the shaft 22 is turned to swing the contact finger 23 downwardly to the dotted line position of Figure 7 out of engagement with contact 19 and in spaced relation to contact 20.

120 As shown, the shaft 22 is provided with a resilient pointer or indicating hand 25, disposed in front of the front wall of casing 8 and adapted to frictionally engage at its free end with the respective lugs 26, 27 and 28 when the finger 23 is adjusted, the pointer 125

25 engaging lug 26 when the finger 23 is in the raised position of Figure 4, being engaged with the lug 27 when the finger 23 is adjusted to the dotted line position of Figure 6 or full line position of Figure 7 and being engaged with the lug 28 when the finger 23 is adjusted to the dotted line position of Figure 7. This frictional engagement of the pointer with the lugs insures 10 maintenance of the finger 23 in the position to which it is adjusted unless the shaft 22 is manually turned. Stop pins 29 are provided on the front wall of the casing in the path of the pointer 25 to prevent the shaft 22 from being turned beyond a limited extent in either direction, thereby limiting the movement of the contact finger 23 to the proper 15 completely raised or lowered positions.

The contacts 19 and 20 and contact fingers 23 may be included in any desired form of 20 alarm circuit, but as shown, the contacts 19 and 20 are connected by a conductor 30 to one side of a battery 31 whose other side is connected to one terminal of an electric bell 32, the contact finger 23 being connected by 25 a conductor 33 with the other terminal of the bell 32, and a single throw switch 34 being interposed in the conductor 33 to render the alarm circuit inoperative in an 30 emergency.

From the above description it will be seen 35 that the controller provides for the sounding of an alarm both when the pressure is partially reduced by opening of a burner controlling valve and when the pressure is unduly reduced or discontinued. It will also be seen that when the burner controlling valve is closed so as to cause the pressure in the expansible chamber to be raised, a further 40 signal is given to remind the attendant of setting the contact finger 23 from the dotted line position of Figure 6 to the full line position of Figures 4 and 6 for proper operation of the alarm should the burner controlling valve be subsequently opened accidentally.

Minor changes may be made without departing from the spirit and scope of the invention as claimed.

We claim:—

50 1. In a pressure operated circuit controller for gas flow alarms, a casing, an expansible chamber through which gas flows mounted in the bottom of the casing and having inlet and outlet ports for connection in a gas supply line, a weighted support mounted on the top of the expansible chamber and carrying a pair of vertically spaced contacts electrically connected together, and a manually vertically adjustable contact finger mounted in the 55 casing in the path of and between said pair of contacts.

2. A device as specified in claim 1, including an operating shaft journaled in the front wall of the casing and contact finger fixed 60 upon the inner end thereof, and means for

limiting the turning movement of the shaft for establishing the upper and lower limits of adjustment of the contact finger.

3. A device as specified in claim 1, wherein said support is in the nature of a pan-shaped member weighted near the front, a vertically swinging bail-connection between the support and the back of the casing to cause vertical movement of the support and the pair of contacts in a definite path, in response to 70 expansion and contraction of the expansible chamber.

4. In a circuit controller of the character described, a manually adjustable contact element, an expansible chamber for the flow of 80 gas therethrough interposed in a gas supply line, a pair of spaced contacts carried by the expansible member and movable by expansion and contraction of the latter in a definite path, said contact element being arranged between and in the path of movement of 85 said pair of contacts, and including a journaled shaft with the contact element extending at right angles therefrom and said shaft being rotatable to move said contact element 90 in the direction of the path of movement of the pair of contacts to provide for circuit closing operations upon partial and total collapse of said expansible chamber and upon complete expansion of said chamber from 95 partially collapsed condition.

5. In a circuit controller of the character described, a manually adjustable contact element, an expansible chamber for the flow of 100 gas therethrough interposed in a gas supply line, a pair of spaced contacts carried by the expansible member and movable by expansion and contraction of the latter in a definite path, said contact element being arranged between and in the path of movement of 105 said pair of contacts, and including a journaled shaft with the contact element extending at right angles therefrom and said shaft being rotatable to move said contact element in the direction of the path of movement of the pair 110 of contacts to provide for circuit closing operation upon partial and total collapse of said expansible chamber and upon complete expansion of said chamber from partially collapsed condition, a casing enclosing the contacts and expansible chamber and a flexible leak proof partition in the casing separating the expansible chamber from the contacts.

In testimony whereof we affix our signatures.
